UNITED STATES PATENT OFFICE.

JOSEPH G. REYNOLDS, OF PROVIDENCE, RHODE ISLAND.

BED-PAN.

SPECIFICATION forming part of Letters Patent No. 336,436, dated February 16, 1886.

Application filed July 10, 1884. Serial No. 137,341. (No model.)

To all whom it may concern:

Be it known that I, JOSEPH G. REYNOLDS, of Providence, in the State of Rhode Island, have invented an Improvement in Bed-Pans, 5 of which the following is a specification.

My invention relates to improvements in a bed-pan adapted for surgical operations; and it consists in the improved construction of the pan, and also in the combination of a flexible 10 siphon-tube therewith, as hereinafter fully set forth.

The figure is a perspective view of a bed-pan provided with my improvement.

In the accompanying drawing, A is the bed-pan 15 provided with the spout a, in connection with the segmental overflow protecting-strip b, secured to the rim f of the pan, and at the rear of the pan is placed the semicircular concaved seat-piece c, secured to the rim f, as in 20 the case of the protector b, leaving the opposite portions of the rim f between the concaved seat c and the overflow-protector b unobstructed, thus adapting the pan for the removal of 25 solids as well as fluids, and for ready access for cleaning purposes.

At the bottom and rear of the pan is inserted the rigid tube d, which is secured to the outer side of the pan and extends upward to near the rim, and to the outer end of the tube 30 d is secured the flexible rubber tube e, provided with the elastic rubber bulb B.

The tube d e and bulb B serve to form a siphon 35 adapted to remove the fluid contents of the bed-pan, and thus prevent the overflow of the same while in use, or the necessity of the removal 40 of the bed-pan from the person for the purpose of discharging the fluid contents, as heretofore.

Upon the application of the bed-pan A to the person and the accumulation of fluid 45 therein the bulb B is to be compressed with the hand, as usual in such devices, the extension-tube e at the lower end of the bulb being

at the same time compressed by the thumb and finger of the other hand, thus performing the 45 function of a valve, when, upon releasing the bulb B from pressure, the fluid in the pan will immediately flow over into the bulb, and upon the removal of the thumb and finger from the lower extension of the tube e a siphon 50 will be established for removing the fluid from the pan.

It will of course be understood that a valve or valves may be employed with the bulb for establishing the siphon-connection; but the 55 employment of valves is deemed objectionable on account of the nature of the fluids to be discharged; but such valves may be used, if desired. The bed-pan may also in common cases be used without the siphon-tube, the improved 60 construction of the pan specially adapting the same for such use.

I am aware that it is not new to provide a bed-pan with a concaved seat and a discharging-spout, or with an overflow-protector for 65 the spout. I am also aware that it is not new to attach a flexible tube to a bed-pan for the purpose of drawing off the fluid contents of the same, and also that a siphon having its discharge end or nozzle enlarged has long been 70 known. I therefore make no claim to any of these parts taken separately.

I claim as my invention—

In a bed-pan having an overflow-protector, the combination of a rigid tube extending from 75 the rear lower corner of the pan obliquely upward to near the upper edge at the side of the same, a flexible tube attached to the outer end of the rigid tube, and the elastic bulb adapted to start the siphon for the discharge of the 80 fluid contents of the pan, substantially as described.

JOSEPH G. REYNOLDS.
